CLAIM

I claim the ornamental design for a bicycle carrier, as shown and described.

DESCRIPTION

FIG. 1 is a top, front, and right side perspective view of a bicycle carrier showing my new design;

FIG. 2 is a front elevational view thereof;

FIG. 3 is a rear elevational view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top, rear, and left side perspective view thereof; and,

FIG. 9 is a partially enlarged view of FIG. 8.

The broken lines in the drawings illustrate portions of the bicycle carrier which form no part of the claimed design.
